HOUSEHOLD APPLIANCE

Peter M. Petersen, Kenosha, Wis., assignor to
S. C. Johnson & Son, Inc., Racine, Wis.

Application April 20, 1948, Serial No. 22,192

2 Claims. (Cl. 306—29)

1

This invention relates to improvements in household appliances. More particularly, the invention relates to an improved applicator or holder which may be used to mount any one of a select group of work elements adapted to be used for maintenance of floors.

Various devices are now on the market for the maintenance of floors. It is common practice for a housewife to use a mop, brush, steel wool or wax applicator in the care of floors. Several holders have been proposed into which interchangeable work elements such as a mop, brush, or wax applicator may be positioned. However, difficulty has been experienced in providing a holder into which an interchangeable work element may be easily positioned which will hold the work element securely when pressure is applied when necessary for efficient mopping or scrubbing.

It is, therefore, a primary object of the invention to provide an inexpensive, yet efficient applicator or holder which comprises a resilient sheet material bent transversely to define an elongated central body portion having converging sides. These sides are provided with gripping portions adapted to hold securely an interchangeable member. The gripping portions of the sides are so positioned relative to the apex of the body portion that when pressure is exerted downward the transmission of pressure through the side members is in an inward direction.

It is a further object of the invention to provide an applicator or holder into which a work element such as a mop, brush, steel wool or wax applicator pad may be easily but yet securely positioned.

Another object of my invention is to provide an applicator or holder adapted to securely hold a work element by the transmission of pressure to the side members in an inward direction.

A further object of the invention is to provide an applicator or holder which may be manufactured and subsequently marketed at a minimum of expense to the ultimate consumer.

Additional objects, advantages and features of the invention will be apparent from the following description considered in connection with the accompanying drawing wherein:

Fig. 1 is a perspective view of a preferred embodiment of the device.

Fig. 2 is a side elevational view of the embodiment illustrated in Fig. 1 showing the representative work element in operating position.

Fig. 3 is a front plan view of the embodiment illustrated in Fig. 1.

Fig. 4 is a perspective view of a work element as representative of the type used with the device illustrated in Figures 1, 2 and 3.

Fig. 5 is a perspective view of another preferred embodiment of the device.

Fig. 6 is a perspective view of a work element as representative of the type used with device illustrated in Fig. 5.

Similar numerals refer to similar parts throughout the several views.

Referring especially to Fig. 1, it will be seen that the applicator, generally designated by the numeral 10, is composed of a transversely bent resilient sheet material 11 and a handle 12 which projects from said bent sheet material 11 at an angle of approximately 30°. The position of the handle may be varied, but care should be taken that the handle is so affixed to the sheet material 11 that the exertion of downward pressure will cause the side members to converge.

When the raised portion 13 of the representative work element, shown in Fig. 4, is positioned inside said resilient sheet material 11 in operating position, gripping portions 14 of said sheet material 11 are forced to expand. The gripping portions 14 fit into the recesses 15 and hold the work piece securely. This expansion is due to the fact that the distance between recesses 15 of the work element is greater than the distance between said gripping portions 14 when in normal position.

In practice, pressure exacted by the user is transmitted through said handle 12 upon said resilient sheet material 11, causing the converging sides of said material 11, to compress said gripping portions 14 into said recesses 15.

Referring now to Fig. 5 illustrating another embodiment of the appliance, it will be seen that auxiliary converging sides 16 bend transversely from gripping portions 17.

The representative work element shown in Fig. 6 is placed into operating position by sliding raised portion 18 into the opening in bent resilient sheet material 19. The upper ridge 20 of said raised portion 18 contacts said sheet material 19 so that said gripping portions 17 are forced to expand. The base 21 of said raised portion 18 is positioned within the inner periphery of said auxiliary converging sides 16. Said base 21 causes said auxiliary sides 16 to expand. Said sides 16, desiring to return to normal position, hold base 21 securely by resilient compression.

When operated, pressure exacted by the user through handle 21, upon said resilient sheet ma-

terial 19 and said auxiliary converging sides 16 causes a convergence of said gripping portions 17 into recesses 22, formed by the in-moving periphery of the work element's upper ridge 20 and the out-moving periphery of base 21. Grip portions 23 of said auxiliary converging sides 16 converge tightly into recesses 24.

Thus, in accordance with my invention, I have provided an efficient household appliance which can be manufactured at a minimum of cost.

It will be apparent from the above that the device provides a multi-purpose household appliance adapted for many different uses, each characterized by convenience, simplicity, and avoidance of contact of the user with the work element.

The work elements were shown as being representative and illustrative of the means by which such element is held fast. It can be readily seen that the character and utility of the working element may be highly variable. Whereas only a brush has been illustrated as a working element, it should be appreciated that steel wool or applicator pads, mops, etc. may be interchangeably employed as work elements.

While the preferred embodiments of the invention have been illustrated and described herein, it will be understood that changes may be made in the construction within the scope of the appended claims without departing from the spirit of the invention.

I claim:

1. A device of the character described consisting of a resilient sheet material bent transversely and continuously in substantially cylindrical shape to define an elongated central body portion having a handle extending obliquely upwardly therefrom and converging sides, said sides having gripping portions adapted to hold securely an interchangeable member, the gripping portions of said sides being so positioned relative to the apex of said body portion so that when pressure is exerted downward upon said handle the transmission of said pressure through said side members is in an inward direction.

sure is exerted downward upon said handle the transmission of said pressure through said side members is in an inward direction.

2. A device of the character described consisting of a resilient sheet material bent transversely and continuously in substantially cylindrical shape to define an elongated central body portion having a handle extending obliquely upwardly therefrom and converging sides, said sides having gripping portions adapted to hold securely an interchangeable member, auxiliary convergingly bent, elongated sides stemming from said gripping portions, said auxiliary sides having gripping portions adapted to aid in holding securely an interchangeable member, the gripping portions of said sides and said auxiliary sides being so positioned relative to the apex of said body portion so that when pressure is exerted downward upon said handle the transmission of pressure through said gripping portions is in an inward direction.

PETER M. PETERSEN.
